UNITED STATES PATENT OFFICE.

JAMES F. SPALDING, OF KANSAS CITY, MISSOURI.

CATHETER-USER'S AROUND-TOWN APPARATUS.

1,100,157.

Specification of Letters Patent. Patented June 16, 1914.

Application filed April 25, 1912. Serial No. 693,249.

To all whom it may concern:

Be it known that I, JAMES F. SPALDING, a citizen of the United States, residing at Kansas City, in the county of Jackson and 5 State of Missouri, have invented certain new and useful Improvements in Catheter-Users' Around-Town Apparatus, of which the following is a specification.

My invention relates to improvements in 10 catheter users' apparatus, and the present invention is especially adapted for use by city salesmen, canvassers, physicians, and others who have a great many calls to make around town in the course of a day, and have frequent need for an apparatus of this character.

The apparatus is exceedingly compact in 15 form so that it may be readily carried in a small valise, the interior of which is provided with means for holding in their proper 20 places the appliances constituting the apparatus.

In order that the invention may be fully 25 understood, reference will now be made to the accompanying drawings, in which:

Figure 1 is a section of the valise in open 30 position on line II-II of Fig. 2, to show the various appliances therein. Fig. 2 is a horizontal section on line III-III of Fig. 30 1. Fig. 3 is a cross section on line IV-IV of Fig. 1. Fig. 4 is a broken elevation of the upper portion of a flexible urinal employed in carrying out the invention. Fig. 5 is a cross section on line VI-VI of Fig. 4.

35 In carrying out my invention, I employ a small valise 1, consisting of a body portion 2 and a lid 3, which latter is secured to the former by hinges 4, so that it may be thrown open to the position shown on Fig. 3.

40 Lid 3 is prevented from swinging backward beyond the position shown on Fig. 3, by a chain 5 attached at its ends to eyes 6 and 7, secured to one side of body 2 and lid 3, respectively. Body 2 is reinforced by a false 45 bottom 8, and lid 3 with a false lid 9, which serve as substantial supporting means for the various holding devices employed to secure the appliances in place when not in use.

10 designates a sponge-containing bowl 50 permanently secured in body 2, near one corner thereof, by a U-shaped holder 11, a narrow space being left between said bowl and the front side of body 2 to receive a towel 12.

13 designates a soap-holder removably secured in one corner of body 2 by a loop 14. 55

15 designates a pair of hangers secured in one side of body 2 by a clasp 16. Each hanger 15 is provided with a short piece of chain 17, secured thereto by a loop 18 and 60 provided at its lower end with a ring 19, for a purpose which will hereinafter appear.

20 designates an extensible cap-band which is held in one corner of the apparatus by 65 clasps 21 and 22, secured to the bottom and rear wall, respectively, of body 2. Said cap-band 20 has a vizor 23 hinged thereto and provided at its upper side with a hood 24 containing a spring-actuated spool carrying a chain or cable 25, provided at its outer 70 end with a catheter clasp 26 for supporting a catheter preparatory to using the same. As cap-band 20 and the parts carried thereby have been fully described in my copending application filed July 5, 1911, Serial No. 75 636,987, further description thereof is deemed unnecessary.

28 designates a flexible urinal held in position on the bottom of body 2 by the cap-band 20 and the hangers 15, which extend 80 over said urinal. The neck of urinal 28 is embraced by a removable collar 29 having a loop 30 fixed to one end to receive its opposite end 32, which is secured in said loop by a thumb-nut 33. Projecting from opposite 85 sides of collar 29 is a pair of hooks 34 to receive the rings 19 of the hanger-chains 17. The mouth of urinal 28 is normally closed by a stopper 35, which is attached to collar 29 by a chain 36 to prevent said stopper from 90 becoming misplaced.

Referring now to the appliances carried in lid 3 of the valise, 37 and 38 designate supply-cases provided at their rear sides with hooks 39 and 40, adapted to engage 95 loops 41 and 42, respectively, secured to lid 3. Supply-cases 37 and 38 are further supported by a bracket 42^a and a U-shaped retaining-rod 43, which latter also holds the respective handles 44 and 45 of said cases in 100 folded position so that they will not strike any of the appliances in the body of the valise when lid 3 is closed. Retaining-rod 43 is loosely-connected at one end to an eye 46 and formed into a hook 47 at its opposite 105 end adapted to detachably-engage eye 48, said eyes 46 and 48 being secured to lid 3, as shown on Fig. 1. Bracket 42^a has a mar-

ginal lip to engage the tops of the supply-cases and thus firmly hold the latter in place. Supply-case 37 contains such articles as a small lap towel 49, a flash-light 50, a bottle 5 of alcohol 51, a collapsible tube of lubricant 52, and absorbent cotton 53. Supply-case 38 is divided into two compartments 54 and 55 for sterilized and used catheters, respectively.

10 Having thus described my invention what I claim and desire to secure by Letters Patent, is:

1. In an apparatus of the character described, two rectangular supply cases removably-secured in the lid of a valise, a bracket to assist in supporting said supply-cases, said bracket having a marginal flange to engage the tops of the supply-cases, and a rod to also assist in holding said supply-

cases in place, said rod being loosely-secured 20 at one end to the lid and removably secured at its opposite end to said lid.

2. In an apparatus of the character described, a valise or the like, loops on the underside of the valise lid, two supply-cases, 25 hooks on said supply cases removably-engaging the loops, and a bracket on the lid coacting with said loops and hooks in securing the supply-cases to the lid, and a retaining rod attached to the lid to coact with 30 the bracket, the loops, and the hooks in securing the supply-cases to the lid.

In testimony whereof I affix my signature, in the presence of two witnesses.

JAMES F. SPALDING.
